UNITED STATES PATENT OFFICE.

MOSES M. MARCUSE, OF NEW YORK, N. Y., ASSIGNOR TO WEST DISINFECTING COMPANY, OF NEW YORK, N. Y., A CORPORATION OF NEW YORK.

SANITARY CLOSET.

1,297,709.

Specification of Letters Patent. Patented Mar. 18, 1919.

Application filed June 10, 1914. Serial No. 844,206.

To all whom it may concern:

Be it known that I, MOSES M. MARCUSE, a citizen of the United States, and resident of the borough of Manhattan, in the city of New York, have invented a new and useful Improvement in Sanitary Closets, of which the following is a specification.

My invention relates to an improvement in sanitary closets with the following objects in view; providing means for disintegrating, agitating, liquefying and disinfecting one or more of the deposits usual to the proper use of the closet; providing a novel and sanitary device for separating the feces and urine, and retaining the same for a considerable length of time without objectionable odor and concealing from view the receptacle containing the foreign matter under certain conditions; attaining these sanitary benefits by mechanism capable of easy operation and simple in construction; providing a sanitary closet which will, when in use, automatically separate a greater or lesser proportion of the urine from the feces; providing a receptacle for the closet which may be easily removed to be emptied or may be left in place and the liquid matter drawn off; providing feces and urine chambers and an outlet passage for either 30 or both chambers; providing means for automatically discharging a predetermined amount of disinfectant into both chambers; providing a registering device for the disinfectant; and providing means for the subsequent treatment of the matter after it has been conveyed from the closet to a predetermined point.

Practical embodiments of my invention are represented in the accompanying drawings, in which—

Figure 1 represents a sectional view illustrating one method of treating the deposits usual to the proper use of a sanitary closet and discharging the same from the confines 45 of the closet from one outlet leading from the urine chamber of the closet,

Fig. 2 represents a view of the same showing the deposits being removed from two outlets leading, respectively, from the feces 50 and urine chambers of the closet,

Fig. 3 represents a view of the same showing the deposits being removed from one outlet leading from the combined feces and urine chamber of the closet,

Fig. 4 represents a transverse vertical section taken from front to rear through the casing, several of the parts being broken away to show more clearly the parts beyond,

Fig. 5 represents a section taken in the plane of the line A—A of Fig. 4,

Fig. 6 represents a plan view with certain of the parts being broken away to show other parts below,

Fig. 7 represents a detail section taken in the plane of the line B—B of Fig. 6, showing the retarding device for the closing of the cover,

Fig. 8 represents a detail central section showing the means of discharging the urine chamber,

Fig. 9 represents a horizontal section taken in the plane of the line C—C of Fig. 4,

Fig. 10 represents a vertical section taken in the plane of the line D—D of Fig. 6, showing the disinfectant tank with its delivery and registering mechanism in section, and

Fig. 11 represents a development of the registering roll.

The casing of the closet is denoted by 1, its base by 2, and a door 3, which is hinged at 4 to the casing.

A seat 5 is hinged at 6 to a back member 7, which is securely fixed to the casing 1 in any well known or approved manner. The seat 5 is provided with a hole 8 of the usual shape, shown in dotted lines in Fig. 4.

A cover 9 is provided for closing upon the seat 5, which cover is also hinged at 6 to the back member 7. The cover 9 has secured to its under side an annular gasket 9* of rubber or other material, so located as to engage the seat 5 when closed and form a seal between the cover and seat, thereby preventing any odor from escaping between the same.

Between the seat 5 and the casing 1 there is located a plate 10 having a tubular body 11 depending therefrom, the lower edges of

which body are oppositely inclined. The plate 10 is removably secured to the casing 1, which prevents the same from becoming displaced by any movement of the seat.

- 5 A pair of flaps 12, 13, fixed to rock shafts 14, 15, mounted in hangers 16, 17, 18, 19, depending from the plate 10, are arranged to close against the inclined lower edges of the tubular body 11, forming a bottom therefor.
- 10 The inner end of the flap 12 is turned downwardly to form eaves 20, and the inner end of the flap 13 formed with a gutter 21. When the flaps 12, 13, are closed, the eaves 20, and gutter 21 coact to direct any liquid matter which falls upon the flaps into the gutter. The gutter and eaves are inclined rearwardly so as to cause the liquid matter which falls therein to be carried to the back and away from the gutter. The gutter extends a slight distance rearwardly beyond the flap 13 for directing the liquid matter into a receptacle, which will be hereinafter explained.

To open the flaps 12, 13, I provide plungers 22, 23, arranged to engage arms 24, 25, fixed to the rock shafts 14, 15, which plungers project upwardly through the plate 10 and are adapted to engage the seat 5 so that when weight is applied to the seat, such as 30 a person using the closet, the plungers will be forced downwardly thereby rocking the shafts and opening the flaps.

It will be understood that the weight of the seat alone is not sufficient to open the flaps, but with the weight of the cover resting upon the seat the plungers will be forced down to the limit of their movement, when the seat will rest upon the plate 10. When the cover is raised the flaps will be closed 40 against the tubular body by springs 26 and weights 27. The springs 26 are mounted on the shafts 14, 15, at the sides of the flaps. The weights 27 are affixed to the outer ends of the flaps, and like the springs, assist in 45 making a complete closure of the flaps against the tubular body, lifting the plungers and the seat.

The position of the plungers with respect to the seat is such that it will require the 50 combined weight of both the seat and cover or the weight of a person on the seat to overcome the action of the springs and weights, forcing the flaps to their open position.

55 The front plungers 22 are under the control of the seat 5, and the rear plungers 23 are under the control of the cover 9.

When the cover is raised from the seat, it takes the additional weight from the seat, 60 and the flaps by their springs and weights immediately close upon the tubular body and raise the seat.

A receptacle 28 is located within the casing 1, and is provided with a partition wall

29 and an upwardly extended bottom 30 so 65 arranged as to form two separate chambers, viz; a feces or solid matter chamber 31, and a urine or liquid matter chamber 32.

To disintegrate the fecal matter deposited within the chamber 32, I mount therein, in 70 opposite corners, rock shafts 33, 34, journaled in bearings 35, 36, upon which shafts I secure a series of beaters 37, 38.

Some of the beaters are provided with tapered blades 39 alternately arranged along 75 the shafts 33, 34, so as to effectively beat and break up the matter falling on the upwardly extended bottom 30.

A series of small radial agitators 40 are also mounted on the rock shafts 33, 34, to 80 agitate the matter falling from the upwardly extended bottom 30 to the rounded corners.

Stationary breaker prongs 40* extend upwardly from the rounded corners of the 85 chamber 31 into the path of the agitators 40, and so coact therewith, breaking up any solid matter that falls to the sides of the chamber from the inclined bottom 30.

The rock shafts carrying the beaters and 90 agitators are controlled and operated from the front plunger 22, seat 5 and cover 9, simultaneously with the flaps, as follows: Vertical rods 41, 42, are slidably mounted in lugs 43, 44, on the receptacle, the lower end 95 of which rods are hinged to arms 45 carried by the rock shafts 33, 34. The upper ends of the rods 41, 42, are each provided with a cap 46, 47, adapted to be engaged by fork shaped members 48, which are connected to 100 the plungers 22 by means of depending arms 49, 50, fixed thereto. Thus it will be seen that as the plungers 22 are raised by the lifting of the seat 5 and cover 9, the vertical rods will rock the shafts through the forked 105 members and force the beaters and agitators down to the position shown in dotted lines in Fig. 5.

The chamber 32 extends forwardly under the bottom 30, into which extension an entrance is effected by means of a flue 51 110 rising from the bottom 30 to within a short distance from the top of the receptacle, the purpose of the flue 51 being to receive any liquid matter which may be directed into a 115 trough 52 fixed to the front of the tubular body. The trough 52 is provided with an outlet at its lower end to which is fixed a spout 53 to insure the liquid matter falling directly into the flue 51.

To draw off some of the liquid matter from the receptacle 28, I provide a cock controlled outlet passage, such as a spigot 54 fixed in a recess 55 in the front wall of the receptacle, which spigot connects with a bypass 56, and to the lower end of the flue 51. When the spigot 54 is turned at right angles to the position shown in dotted lines,

Fig. 9, it will allow the liquid matter to flow from the urine chamber 32 to the level of the spigot, thereby removing a portion of the liquid matter from the chamber without removing the receptacle from the casing.

5 A stop 57, located in the recess 55, arrests the outward movement of the spigot, or places the spigot in such a position that when the door is closed upon it, either by 10 accident or intent, the spigot will be forced into the recess and the liquid matter cut off.

The partition wall 29 is provided near its top with a series of holes 60 which serve as an overflow for the liquid matter from one 15 chamber to the other.

A disinfecting device for automatically discharging a predetermined amount of a disinfecting and liquefying agent into both the feces chamber and the urine chamber, is 20 located within the casing 1 and is constructed and operated as follows: A discharging device, consisting of a tube 62 having a cup 63 at its inner end, is hinged intermediate of its ends to the side of a reservoir 64.

25 The cup 63 is so arranged that when tilted it will pour its contents into the tube 62, which will pass into a receiver 65 fixed to the outside of the reservoir. This receiver 65 is provided with ducts 66, 67, which are located so that the duct 66 will discharge a 30 portion of the contents of the receiver into the chamber 32 and the duct 67 discharge its contents into the chamber 31.

To operate the discharging device, a plunger 68, mounted to slide in the back member 7, is arranged to engage the tube 62 outside the reservoir. A toe 69 is fixed to the cover 9 so as to engage the plunger 68 when the cover 9 is raised. Thus it will be seen 40 that the downward movement of the plunger will tilt the discharging device, the contents of which will be emptied into the receiver 65 and be carried off through the ducts 66, 67, to the chambers 31, 32.

45 To provide for conveniently filling the reservoir a funnel 70 is fixed to the plate 10 directly over the reservoir, and is provided with a cap 71 fitting into the funnel and flush with the top of the plate 10.

50 To register the contents of the reservoir 64, I provide a drum 72 mounted to rotate in a bracket 73 fixed to the under side of the plate 10 directly over the reservoir 64.

A flexible connection 74 is secured to the 55 drum 72 leaving the ends free to engage a float 75 on one end and a counterbalance 76 upon the other, which counterbalance is free to slide within a tubular guide 77 fixed in the reservoir 64. When the reservoir is being filled the float will rise, which transfers the weight of the counterbalance on one side of the drum and rotates it to that side. As 60 the liquid falls, the float, being heavier than the counterbalance, will cause the drum to

rotate to its side and lift the counterbalance 65 in its guide. Upon the periphery of the drum I provide marks or words, such as are shown in the development of the face of the drum, in Fig. 11, viz; "Empty", "Refill" and "Full," arranged at proper distances so that 70 they will be seen through the window 78 located directly above the drum in the plate 10, to indicate the position or the amount of liquid in the reservoir.

To automatically close the cover 9 when 75 the closet is not in use, I provide means controlled by the seat adapted to engage the cover 9, which means is constructed, arranged and operated as follows: A push lever 79 having a depending arm 80 is mounted 80 to rock in a bracket 81 secured to the back member 7, with the depending arm 80 passing through a hole 82 in the back member. A rocking lever 83, is mounted to rock in a bracket 84 depending from the back 85 member 7, one end of which is adapted to engage an abutment 85 secured to a flexible connection 86, which passes over a pulley 87 and is attached to the depending arm 80.

A weight 88 is secured to the opposite 90 end of the flexible connection 86 for forcing the lever 79 forward.

A rod 89 hinged at 90 to the seat 5 is provided with jam nuts 91 adjustable on the rod, in position to engage the other end of 95 the rocking lever 83 for lifting the weight from its bracket 92 and relieving the tension on the arm 80 and push lever 79, which will fall to a resting position as shown in Fig. 4, 100 until the cover is again raised.

The parts are so arranged that the push lever 79 is normally at rest when the seat and cover are down. The first movement in raising the cover causes the seat to rise, allowing the jam nuts 91 on the depending 105 rod 89 to rise and the weight 88 hanging from the end of the lever 83 by the abutment 85, to pull on the depending arm 80 and force the push lever 79 forward as shown in dotted outline in Fig. 4. The further movement of the cover causes the push lever to be forced back, which will take the weight from its seat, and the weight being heavier than the cover tends to force it back 110 past its center, where, if released, it will fall by gravity to its closed position.

To provide for the cover closing noiselessly and to prevent the sudden jar which might be caused by the quick action of the push lever 79, I hinge on the cover at 93 120 a rod 94, the free end of which is provided with a roller 95 adapted to engage a spring pressed plunger 96 located in a recess 97 in the seat 5.

To assist the plunger 96 and arrest the 125 cover in its first downward movement, the rod 94 and roller 95 will be engaged between a flat spring 98 and the upper wall of the

recess 97. This action will retard the downward travel of the cover before it reaches the spring pressed plunger, where finally it rests.

- 5 To insure the carrying off of all odors within the casing 1, I arrange a series of holes 99 near the bottom, which, with a ventilating pipe 100 situated at the back of the casing, tend to induce a current of air 10 to pass upwardly through the casing and out through the ventilating pipe 100.

When the closet is to be used, the cover is raised from the seat, which takes the additional weight off the seat and the flaps 15 by the action of the springs and weights, close upon the tubular body and conceal from view the contents of the feces chamber. Simultaneously with the raising of the cover, the seat is caused to lift by the 20 action of the plungers and the disinfecting device caused to discharge a predetermined amount of disinfectant into both the feces chamber and the urine chamber.

Upon the seating of the person using the 25 closet, the flaps will immediately open, permitting direct access to the feces chamber. The solid matter falling upon the ridge of the upwardly extending portion of the bottom, will be caused to travel down the inclined bottom to the sides of the chamber, which, should there be any liquid therein, will prevent any splashing by the falling of the solid matter therein. The urine passing from the person using the commode will 30 enter the trough 52, pass through the spout 53 into the flue 51, thence into the urine chamber 32, thereby keeping the feces chamber free from urine and the liquid and solid matter separated.

40 When the person rises from the seat, it will be forced upwardly by the plungers, and the cover will be pushed past its center by the action of the weight 88 on the arm 80 and push lever 79, where it will fall to its position on the seat, closing the same tightly upon the plate 10 and casing.

To provide for males using the closet to urinate without being seated, after the cover is raised, the seat is raised or the cover and seat may be raised together. In either event the flaps 12, 13, will close upon the tubular body with the gutter and eaves in position at the bottom of the body. The person may now urinate upon the flaps, which urine will 55 pass into the gutter 21 and travel rearwardly with the downward inclination of the gutter and be carried directly to the urine chamber. The contents of the urine chamber may be drawn off from time to time 60 through the spigot, without removing the receptacle from the casing 1. The receptacle 28 may be removed from the casing to be emptied and cleaned through the door 3.

I also provide means whereby the disinfected disintegrated deposits may be con-

veyed away from the confines of the commode to a predetermined point, where it is collected and treated with a further disinfecting liquefying agent, from whence it passes out into the ground or elsewhere. 70 To this end, it will be seen that in Figs. 1 and 4 a pipe connection 101 is carried from the discharge outlet of the receptacle 28 in the commode to a receiving tank 102, which may be placed beneath the level of the 75 ground and which is provided with baffle plates 103 and an outlet 104, from which it passes out into the ground.

The receiving tank is also provided with a vertical pipe 105, which may extend upwardly with the end above the ground and having a cap 106 thereon. The purpose of this pipe 105 is to deposit a disinfecting agent or to clean out the receptacle if so desired. 80

In the forms shown in Figs. 2 and 8, the closet is provided with a discharge outlet 107 for the urine chamber, as well as the pipe connection 101, both of which outlets lead to the receiving tank 102. 90

In the form shown in Fig. 3, the receptacle has a single chamber 108, into which both the feces and the urine are deposited together. In this form, the disintegrating device 109 extends the entire length of the 95 receptacle and is controlled and operated as previously described. This receptacle has a discharge outlet 110 which leads to the receiving tank.

It will be seen that by the construction and arrangement of the several parts of this 100 closet, flies and other insects will be excluded from the receptacle at all times by the flaps when the cover is opened and by the cover when closed.

What I claim is:—

1. A sanitary closet having a receptacle divided into separate chambers for the feces and urine, a seat, an agitator having radially disposed prongs and a disintegrator 110 having radially disposed beaters, said agitator and disintegrator being located within the feces chamber and operated by the seat.

2. A sanitary closet having a seat, a receptacle divided into separate feces and urine 115 chambers, a combined agitator and disintegrator located in said feces chamber and adapted to be operated by the movement of the seat, said agitator and disintegrator comprising shafts horizontally mounted in 120 the feces chamber, beaters and prongs carried by said shafts, and stationary prongs uprising from the bottom of the chamber intermediate the prongs and beaters and in position to coact with the prongs on the 125 shafts.

3. A sanitary closet having a seat, a receptacle divided into separate feces and urine chambers, the bottom of said feces chamber provided with a centrally disposed ridge, 130

shafts horizontally mounted upon opposite sides of said ridge, beaters and prongs carried by said shafts, stationary prongs ⁵ uprising from the bottom of said feces chamber intermediate the beaters and prongs and in position to coact with the prongs on the shafts, and means controlled by the movement of the seat for oscillating said beaters and prongs.

Copies of this patent may be obtained for five cents each, by addressing the "Commissioner of Patents, Washington, D. C."

In testimony, that I claim the foregoing as ¹⁰ my invention, I have signed my name in presence of two witnesses, this twenty second day of May, 1914.

MOSES M. MARCUSE.
